Attorney.

UNITED STATES PATENT OFFICE.

JOHN SMITH, OF BALTIMORE, MARYLAND.

BALING-PRESS.

SPECIFICATION forming part of Letters Patent No. 233,812, dated October 26, 1880.

Application filed September 1, 1880. (No model.)

To all whom it may concern:

Be it known that I, JOHN SMITH, of Baltimore city, State of Maryland, have invented certain new and useful Improvements in Bal-
5 ing-Presses; and I hereby declare the same to be fully, clearly, and exactly described as follows, reference being had to the accompanying drawings, in which—

Figure 1 is an end elevation of the press, 10 and Fig. 2 is a side elevation of the chain-drum.

My invention relates to hay, straw, or cotton presses in general, and to that class of the same in which the follower is lifted by 15 means of a chain wound upon a conical or tapering drum actuated by means of a ratchet-wheel, pawl, and lever.

My invention consists in an improved mechanism for operating the ratchet-wheel, as here-
20 inafter set forth.

Proceeding to a description of the mechanism whereby these ends are attained, and referring to the accompanying drawings, A is the press-body, having the usual end beams, 25 A' A'', hinged side A'', top beam, C, secured by links B, that are hinged to a cross-bar, b, lever D, and pawl H. These parts are all of the ordinary construction and operate in the usual way.

30 E' is a link embracing the lever D, and serving as a fulcrum-rod for the same, and connected thereto at its end, and is also attached to the shaft f of the drum I, turning freely thereon.

35 A link, a, pivoted to the end of the lever D, engages with the teeth of the wheel G, and a second link or pawl, E, pivoted to the lever at some distance from its end, also engages with the teeth of the wheel, as shown. Both 40 links are pressed into engagement with the teeth by means of a double-leaf spring, c, having arms c' c''.

One side of the press is hinged, as usual,

at h, and the side beams are secured by catches e e.

On the shaft f is keyed a tapering drum, I, 45 around which the chain i, that is attached to the follower-beam J, is wound. This drum is provided with a groove, K, of a width equal to the thickness of the links, and of a depth 50 equal to the part of the link that projects laterally beyond the plane of the adjacent links, the design being to so conform the groove to the links that the latter will wrap smoothly on the drum, every other link lying in a plane 55 about at right angles with the shaft, and the others flatwise on the face of the drum. By these means, as the chain is wound up, each link falls smoothly in place and the chain is not twisted.

In operation, as the lever D is depressed, the links a and E engage with the teeth of the ratchet-wheel G, the link a operating to pull and the link E to push and turn the drum, winding the chain thereon and lifting the fol- 65 lower.

At first the effective leverage is slight, by reason of the large radius of the drum at its outer end, and the follower rises swiftly. As the contents of the press become condensed, 70 the effective leverage increases, the chain winding then on the small end of the drum. Engaging, as it does, with two teeth of the wheel, the lever distributes its strain, and the danger of breakage is lessened.

75 What I claim is—

1. In combination with the lever D, having links E a, and the spring c, the ratchet-wheel, drum, chain, and follower, as set forth.

2. In combination with the ratchet-wheel 80 and pawl H, the link E', lever D, spring c, having arms c' c'', and links E a, as set forth.

JOHN SMITH.

Attest:

R. D. WILLIAMS,
JOHN C. GITTERER.
